JOSEPH LOUIS KIEFFER, OF MONTREAL, CANADA.

NEEDLE-GUIDE MECHANISM FOR SEWING-MACHINES.

SPECIFICATION forming part of Letters Patent No. 737,417, dated August 25, 1903.

Application filed August 24, 1901. Serial No. 73,201. (No model.)

To all whom it may concern:

Be it known that I, JOSEPH LOUIS KIEFFER, a subject of His Majesty the King of Great Britain, residing in the city and district of 5 Montreal, Province of Quebec, Canada, have invented certain new and useful Improvements in Needle-Guide Mechanism for Sewing-Machines; and I do hereby declare that the following is a full, clear, and exact description of the invention, such as will enable others skilled in the art to which it appertains to make and use the same.

My invention relates to improvements in sewing-machines of the class used in sewing boots and shoes by a single-thread chain-stitch and employing a stitch-forming mechanism embracing a curved hooked needle adapted to be alternately advanced through and retracted from the work and a looper arm 20 ranged to conduct the thread in a loop around the path of the needle and cause the thread to be engaged with the hook of the needle, whereby the stitching is advanced in the well-known manner of chain-stitch sewing-machines of this type.

The specific improvement which I have in view in the present specification is connected with the structure and arrangement of the guide-piece which is commonly used to hold the needle at an intermediate point thereof between the hooked end and the block or carrier to which it is secured, and this improved structure may accordingly be used not simply in the class of machines hereinafter referred to and one of which is illustrated in the present specification, but in any form of machine which employs a curved or arcuate needle which reciprocates or oscillates about a fixed center.

Movable guides for the needle, adapted to hold the same in line to prevent bending and breakage, are common in this class of machinery; but the principal difficulty common to all needle-guides at present known to the 45 art is that these guides are so supported that they have insufficient bearing-surfaces either upon their flat cheek-surfaces or upon the cylindrical bearing-surfaces adjacent to the spindle or journal carrying them, and by 50 reason of the structure employed it was not possible to make this bearing-surface sufficiently large and to place it in such a manner

as to prevent the rapid wearing loose of the needle-guide, whereby it was caused to rattle and wabble laterally in its bearings, and thereby its function in guiding the needle into the precise point of the work intended for it, as well as for minimizing breakage, was but very imperfectly fulfilled.

It has been my object in the present invention to correct this defect by providing a new and different structure for supporting the needle-guide, whereby a very large and long bearing-surface is provided and, moreover, the needle-guide is firmly held against any possible lateral shifting or wobbling, being solidly secured to the parts with which it turns in such a manner that in the operation of the machine they perform the same function as though they were integral with each other—that is to say, as if the needle-guide were made an integral part of the parts with which it turns. The special feature by which this object is accomplished consists in providing an oscillating spindle or rock-shaft, on the end of which the needle-guide is solidly mounted, and the end on which the needle-guide is mounted is accordingly enlarged to form a circumferential flanged head, which forms a means of holding the needle-block in place. In previous machines the needle-block and needle-guide were mounted separately on the projecting end of a sleeve or bushing mounted in the work-head of the machine, which sleeve was provided with an enlarged circumferential head to hold them in place and the sleeve was itself held in place in the work-head by the friction of a setscrew abutting against the side of said sleeve; but said means have been found to be wholly inadequate to prevent the working loose of the oscillating parts by the lateral pry or leverage exerted by them during the operation of the machine, so that it was impossible to keep the parts tight for more than a few minutes at a time, and, moreover, the construction above mentioned left an excessive amount of friction, due to the bearing-surfaces of the parts rubbing against each other. In my construction, on the contrary, the said circumferential sleeve is formed plain and without any head, the essential function of this sleeve being to form a bearing-support for the rock-shaft and needle-block, but not for the nee-

idle-guide, because the needle-guide is solidly mounted on the bolt or rock-shaft arranged to oscillate within said sleeve, as above mentioned. It will appear from the sequel, moreover, that the collocation of the parts is such that the needle-guide and rock-shafts may be made in one piece, if desirable, or welded, soldered, or otherwise permanently made integral with each other, although for ease of 10 mechanical construction and renewal of the parts I prefer to make the needle-guide and rock-shaft separately and secure them together in the manner above indicated. Although in the operation of the machine the 15 two parts work as one, I wish it to be understood that they are separately constructed simply in order that the machine may be more easily manufactured and that new parts may be more easily substituted for old and 20 worn ones. Moreover, the end thrust upon the sleeve is wholly removed in my device, and means are provided for properly adjusting the parts against wear in such a manner that they cannot possibly be worked loose by 25 the lateral prying of the oscillating parts, because the needle-block is held between the work-head of the machine and the said circumferential flange on the end of the bolt or rock-shaft which forms a part of the needle- 30 guide, and I provide means, such as lock-nuts, on the opposite end of the shaft for shortening the effective length of the shaft, and thus drawing the oscillating parts together to exactly the proper extent to make 35 them tight, while permitting of easy movement.

Another object had in view in the present invention is that of providing an adjustable stop for the reciprocating travel of the needle-guide, so as to provide for different positions of the work-gage, which will necessarily be differently adjusted to different thicknesses of stock. Heretofore in the art any such adjusting means has not been provided, 40 and by reason of this fact the forward movement of the needle-guide had to be limited to the position corresponding to the rearmost position of the work-gage, and thereby when the work-gage was in its forward position 45 the needle-guide did not fulfil its purpose to the best advantage in that it could not be projected forwardly to correspond with the advanced position of the work-gage, and thus support the needle in its movement at a point 50 closer to the point of the needle. In providing my adjustable stop, which is in the form of a cam-plate located in the path of an oscillating part of the needle-guide structure, I therefore provide for adjusting the forward 55 movement of the needle-guide to the most advantageous degree in each instance, and this is an improvement which, so far as I am 60 able to learn, is entirely new in the art.

The particular construction and combination of parts wherein my invention consists 65 and the special features and advantages thereof will appear more exactly from exami-

nation of the following description in connection with the accompanying drawings.

In the drawings, Figure 1 is a side elevation from the left side of a machine embodying my improvement. Fig. 2 is an enlarged view, in side elevation, from the right side of the machine of the curved needle, its carrier, the needle-guide, and the other parts immediately associated therewith, the end of the needle-guide being shown in section. Fig. 3 is a vertical cross-section through the head of the machine upon the line 3 3 of Fig. 2. Fig. 4 is an enlarged view showing the headed spindle operating the needle-guide. Fig. 5 is a similar view of the needle-guide. Fig. 6 is a similar view of the crank or rocking arm which operates the needle-guide. Fig. 7 is a similar view of my adjustable stop. 85

The same numerals of reference denote like parts in all the figures of the drawings.

My improvement in the present instance is embraced entirely in that portion of the machine shown in Figs. 2 and 3—that is to say, in 90 the needle-bearing head, as shown upon the right central portion of Fig. 1—and the other parts of the apparatus shown in Fig. 1 do not concern my present invention, this figure being merely intended to show in a general way a 95 shoe-sewing machine of this type and to indicate the manner in which my present improvements are disposed with relation to that machine, so that it will be unnecessary to enter into a detailed description of all the parts 100 shown in Fig. 1, as these are of the ordinary form known to the art and will be well understood by those versed in such machinery, with the exception of the improved take-up mechanism, which is shown in the parts 10 numbered 77 to 97, inclusive, of my present drawings and which forms the subject of my divisional application, serially numbered 82,287, filed November 14, 1901, and my improved pull-off mechanism shown at the extreme left of Fig. 1 of the present drawings 110 and indicated by the numerals 101 to 112, inclusive, and which forms the subject of my divisional application Serial No. 82,288, filed November 14, 1901, and for a special description 115 of these devices reference may be had to the specifications of those applications, respectively.

The needle-bearing or work head of the machine is indicated by the numeral 24, and 120 through this head is bored a transverse cylindrical aperture, which forms the seat for a cylindrical sleeve or bushing 29, which is driven thereinto and normally stationary therein. The sleeve or bushing 29 on the left side of 125 the head 24 is flush therewith, and on the right side it extends beyond the side of the head to form a journal-support for the needle-block 23, which is mounted to oscillate thereon and to be oscillated by a link 130 23^a, which is connected at its lower end to a suitable cam-lever operated from the main shaft 5 of the machine, as will be well understood, the link 23^a being provided at its lower

end with an aperture 23^b for the passage of the bolt connecting it with said lever. The link 23^a is connected at its upper end to a piece 43, firmly secured to the needle-block 23 and having on its forward end a projecting nose 43^a, the purpose of which will be hereinafter described.

Referring briefly to Fig. 1, it will be observed that the apparatus shown is provided with a looper 8 directly in front of the needle and mounted upon a looper-bar 9, having a universal movement and operated, together with the needle and the other operative parts of the machine, by a series of cams 92 upon the shaft 5, as will be well understood by reference to the prior art and need not be herein further described. Below the needle and adjacent to the path thereof is the adjustable work-gage 15, which is mounted on the end of a bar 16 and interlocks with a suitable gear upon a shaft 17, the work-gage being pressed forward in the usual manner by a spring-coil about the shaft 17 and locked in its forward position at the proper intervals by a reciprocating pawl engaging with the teeth of a ratchet-wheel on the shaft 17, all as clearly shown in the drawings and as in the usual form of this type of machine. I have also shown a similarly-operating back gage 18, mounted on a reciprocating rod 19, which is likewise spring-pressed into its forward position and locked at the proper intervals against backward movement by the serrated catch-plates 20 and 21, the latter being mounted to oscillate upon the shaft 87 and operated by the cam-lever 90, engaging with the cam-groove 91, and caused to move downwardly at the proper intervals by the jog 91^a in said groove.

Returning now to the parts shown more specifically in the detail views of my invention, it will be seen that I have provided upon the right-hand side of the head 24 a suitable arcuate guideway 25 for the needle-block 23, said guideway having an overhanging flange to retain the needle-block in place, all of which is old and forms no part of my invention. The curved or arc-shaped needle of the usual type is shown at 13 and provided at its outer end with a hook 14, and this needle is secured to the needle-block by a suitable plate 23^c and firmly held in place by the nut 23^d, turning on the slotted bolt 23^e, as is customary in this form of device. The needle-guide itself (indicated by the numeral 22 and shown in enlarged detail in Fig. 5) is also not new with me, this needle-guide consisting of a ring portion 26, having a downwardly-extending finger 26^a, through which is formed a longitudinal aperture 27, through which the needle 13 is adapted to pass, and the needle is adapted to slide loosely therein and to be guided thereby. The central aperture 26^b of the ring-portion 26 is made of the same diameter as the exterior diameter of the sleeve 29, whereby the needle-guide is adapted to fit and to turn easily, but without lost motion, on

the said spindle, and this needle-guide has on the opposite side from the flinger 26^a a projecting jog 43^b, which is so placed as to be engaged at the proper intervals by the nose 43^a upon the piece 43 when the latter is turned to retract the needle from the work, whereby said needle-guide is turned with the needle beyond a certain point of its backward movement in order to prevent the point of the needle passing out of the aperture 27. Both the cheeks of the ring 26 are planed parallel and faced, the left-hand cheek abutting against the right-hand cheek of the needle-block, as shown, while the right-hand or exterior cheek is flush with the outer end of the sleeve 29 and forms a close junction and abutment with the inner side of a circular head 32, formed upon the end of the spindle or rock-shaft 31, which is made to fit inside said sleeve and to turn therein without lost motion. In order to connect the needle-guide firmly with this head, which gives it its motion, there is a pin 28 embedded in and projecting laterally from the abutting cheek of the ring 26, and this pin projects into a corresponding aperture 34, formed in the depending ear 33, which is formed on the circumference of the circular head 32. The rock-shaft 31 is of such length that it passes entirely through the sleeve 29 and projects from the left-hand side thereof to a certain extent and at its outer end is reduced in diameter to form a screw-threaded projecting stud 37. At the base of this screw-threaded portion the shaft 31 is formed with an appropriate flattened portion 36 of any suitable form, and over this projecting end portion is passed the hub 39 of a crank or rock-arm 38, which is correspondingly formed to fit the flattened portion 36, and it is firmly secured to the rock-shaft by a pair of nuts 35, which being turned into proper position and the needle-guide 22 and needle-block 23 being in place secure the whole mechanism in proper relation and prevent any possible lost motion from any source. The rock-arm 38 is provided with a laterally-extending pin 40, to which is connected one end of a suitable helical spring 41, whose other end is secured to any suitable stationary part of the frame of the machine—as, for instance, to a screw-stud 42, screwed into the frame. Now it will be seen that this spring connection 41 operates upon the rock-arm 38 and rock-shaft 31, and so upon the needle-guide 22, through the pin 28 to keep it pressed into its foremost position, and it maintains this position so long as the needle is advanced, as shown in Fig. 2; but when the needle is retracted the nose 43^a will then strike against the jog 43^b and cause the needle-guide, with its attachments, to be turned backwardly against the tension of the spring 41, and this position is shown in Fig. 1 of the drawings.

In order to form an adjustable limit to the forward path of the needle-guide, whereby the same may be adjusted to the special position of the work-gage 15 and yet not inter-

fere with the action of the needle, I have shown upon the left of the work-head 24 an adjustable stop-plate 44, which is shown in enlarged detail in Fig. 7. This stop may be 5 in different forms, but consists, preferably, of a sector-shaped plate having an aperture in one end, through which passes a screw-stud 45, securing it to the head, while the opposite end is provided with an arcuate slot 10 47, concentric with its point of rotation and through which passes an adjusting-screw 48, which is likewise screwed into the head 24 and is adapted to secure the plate 44 in any position, as will be seen. The essential feature of the plate consists in the cam or eccentric edge 46, which being at a variable distance from the central point 45 of the plate will project to variable points in the path of the rock-arm 38, according to the position at 15 which it may be adjusted. For instance, in the position shown in Fig. 1 the stop-plate is adjusted so as to give the rock-arm and needle-guide its shortest throw—that is to say, the needle-guide will be adjusted to the most 20 backward position of the work-gage.

The special advantages accruing from my improved structure of the needle-guide are many. In the first place, it will be seen that the needle-guide being firmly secured against 25 the large flat surface of the head 32 forms practically a solid piece with the rock-shaft so far as its operation is concerned, and thus gives it the advantage of the entire bearing-surface of the said shaft, together with the 30 additional bearing-surface which it ordinarily has against the exterior surface of the sleeve 29 and against the cheek of the needle-block. In the second place, the needle-guide may be rapidly removed and replaced for cleaning, 35 renewal, repairs, or inspection, as may be desired, by simply removing the nuts 35, and this will not necessitate in any way the disarrangement or removal of the stationary sleeve 29. A third advantage is that the friction is minimized 40 by reason of having only a single thrust-bearing for the needle-guide—that is to say, that which is formed by its abutment against the cheek of the needle-block—because the opposite cheek is not subject to 45 wear nor to friction, being firmly secured to and oscillating with the head 32, and a fourth great advantage of my structure is that the wear between the oscillating parts, such as it may be, although it will be small in any case, 50 is readily taken up by simply adjusting the two jam-nuts 35 on the end of the spindle, and no such provision for adjustment against wear has been shown, so far as I know, in any heretofore-existing machine, so that it 55 was heretofore necessary either to continue to use worn-out parts after the needle-guide had worn so much as to be practically useless or else to replace them at considerable expense, and even the replacement of the needle-guide was not sufficient, because of the 60 additional wear upon the bearings, which by

reason of the small bearing-surface was rapid. Hence it is thought that from these remarks the advantages of my improved construction will now be apparent.

It will be obvious from the above description that the needle-guide piece 22 and rock-shaft 31, although made separately, as described, are yet so collocated with respect to each other that they may be solidly and permanently welded, soldered, or otherwise secured together, if desirable, or the two pieces thus shown may be cast or otherwise formed in one single piece, all without interfering in the slightest degree with the setting up or 70 assembling of the parts or their taking apart, adjustment, or in their manipulation. This, so far as I am aware, has not been the case with any construction yet known in the art. The reason for making the needle-guide and 75 rock-shaft separately and forming the flanged head 32 on the latter is purely one of mechanical convenience of construction and to enable the needle-guide and rock-shaft to be renewed separately, as one will necessarily 80 become worn out faster than the other. I do not, therefore, in any way limit myself to the two-piece construction, as I deem a one-piece construction the full equivalent therefor, as indicated by the scope of the following claims; 85 nor do I, on the other hand, in any way limit myself to the particular method described of securing my needle-guide to the end of the rock-shaft, as numerous other ways of securing the shaft and guide together will be readily devised by any skilled mechanic as may 90 seem suitable for securing the desired end above pointed out, the essential point being always that the needle-guide and rock-shaft shall be solidly secured together during 95 operation, so that the needle-guide takes its main or entire support from the rock-shaft. In this latter connection it is to be noted that while in the present drawings I have shown a needle-guide annulus 26 as surrounding and 100 inclosing the end of the sleeve 29, so that it may have a bearing upon the latter, yet it is not at all essential to the principle of my invention that the needle-guide bear directly 105 on the outer surface of the sleeve 29, or even 110 surround the latter; but this construction gives it an additional bearing in conjunction with the end of the rock-shaft which still further strengthens and rigidifies the oscillatory motion of the needle-guide to prevent 115 wabbling, as will be obvious; nor do I limit myself to the precise form of the other parts 120 of my invention herein described, for it will be obvious to those skilled in the art that many of the details may be changed in form 125 or position without affecting the operativeness or utility of my invention, while still preserving the principle, and I therefore reserve the right to make all such modifications as are included within the scope of the following claims or of mechanical equivalents 130 to the structure set forth.

Having thus described my invention, what I claim as new, and desire to secure by Letters Patent, is—

1. In a sewing-machine, a needle-guide mechanism comprising a stationary sleeve or bushing mounted in the head of the machine and projecting therefrom, a rock-shaft mounted in said bushing and having a flanged head projecting circumferentially from the projecting end of said bushing, and a needle-guide piece abutting against said flanged head and secured thereto. 5
2. In a sewing-machine, a needle-guide mechanism comprising a stationary sleeve or bushing mounted in the head of the machine and projecting therefrom, a rock-shaft mounted in said bushing and having a flanged head projecting circumferentially from the projecting end of said bushing, and a needle-guide piece abutting against said flanged head and secured thereto and surrounding the outer surface of said bushing. 10
3. In a shoe-sewing machine, a needle-guide mechanism comprising a stationary sleeve or bushing mounted in the head of the machine and projecting therefrom at one end, a rock-shaft journaled in said bushing and having a circular flanged head projecting circumferentially around the projecting end of said bushing, a needle-guide piece having a depending finger embracing the needle and abutting against the interior side of said flanged head and surrounding the end of said bushing, and a pin connecting said flanged head and guide-piece. 15
4. In a shoe-sewing machine, a needle-guide mechanism comprising a stationary sleeve or bushing mounted in the head of the machine and projecting therefrom at one end, a rock-shaft journaled in said bushing and having a circular flanged head projecting circumferentially around the projecting end of said bushing, a needle-guide piece having a depending finger embracing the needle and abutting against the interior side of said flanged head and surrounding the end of said bushing, a pin connecting said flanged head and guide-piece, and a needle-block mounted to oscillate upon the exterior of said bushing between said guide-piece and the work-head. 20
5. In a shoe-sewing machine, a needle-guide mechanism comprising a stationary sleeve or bushing mounted in the head of the machine and projecting therefrom at one end, a rock-shaft journaled in said bushing and having a circular flanged head projecting circumferentially around the projecting end of said bushing, a needle-guide piece having a depending finger embracing the needle and abutting against the interior side of said flanged head and surrounding the end of said bushing, a pin connecting said flanged head and guide-piece, a needle-block mounted to oscillate upon the exterior of said bushing between said guide-piece and the work-head, and means for holding said guide-piece yieldably at the forward end of its stroke. 25
6. In a shoe-sewing machine, a needle-guide mechanism comprising a stationary sleeve or bushing mounted in the head of the machine and projecting therefrom at one end, a rock-shaft journaled in said bushing and having a circular flanged head projecting circumferentially around the projecting end of said bushing, a needle-guide piece having a depending finger embracing the needle and abutting against the interior side of said flanged head and surrounding the end of said bushing, a pin connecting said flanged head and guide-piece, a needle-block mounted to oscillate upon the exterior of said bushing between said guide-piece and the work-head, a rock-arm keyed upon said rock-shaft at the opposite side of the head, adjustable tightening means such as nuts, for drawing the parts together to take up wear, and a spring secured at one end to the end of said rock-shaft and at the opposite end to a stationary part of the machine, whereby to yieldingly retain said needle-guide at the foremost end of its stroke. 30
7. In a sewing-machine of the class described, the combination with a needle-guide, of a spindle secured fast to said needle-guide, and means for adjusting the rocking movement of the spindle and the arc of vibration of the needle-guide, substantially as described. 35
8. In a sewing-machine of the class described, the combination with a needle-guide, of a bushing, a spindle mounted in the bushing and secured fast to the needle-guide, an arm on the spindle, and a stop-plate secured adjustably in the path of said arm, substantially as described. 40
9. In a sewing-machine of the class described, the combination with a rock-shaft and a needle-guide attached thereto of a rock-arm keyed upon said rock-shaft, and an adjustable stop-plate adapted to project to variable distances into the path of said rock-arm. 45
10. In a sewing-machine of the class described, the combination with a needle-guide, of a bushing, a spindle mounted in the bushing and secured fast to the needle-guide, an arm on the spindle, and a sector-shaped slotted plate having a cam edge adapted to be projected to variable distances into the path of said rock-arm. 50
11. In a sewing-machine, a needle-guide mechanism comprising a plain cylindrical sleeve or bushing mounted in the head of the machine and formed without stud or projection thereon and having one end projecting laterally from the head of the machine, a rock-shaft mounted in said bushing and having a flanged head projecting circumferentially from the projecting end of said bushing, and a needle-guide piece abutting against said flanged head and secured thereto. 55
12. In a sewing-machine, a needle-guide mechanism comprising a stationary sleeve or bushing mounted in the head of the machine and projecting therefrom, a rock-shaft mount-

- ed in said bushing and having a flanged head projecting laterally beyond the end of said sleeve, a needle-guide piece abutting against said flanged head and secured thereto, a needle-block mounted to turn on the projecting end of said sleeve or bushing between the work-head and the inner face of said needle-guide, and means for drawing the parts together into tightened relation comprising lock-nuts secured upon the end of said rock-shaft opposite the flanged head thereof.
13. In a needle-guide mechanism, the combination of a needle-guide, and a coaxial spindle having a projecting end to which said needle-guide is directly secured whereby the spindle and needle-guide may be together mounted and dismounted.
14. In a sewing-machine, a needle-guide mechanism comprising a rock-shaft, a needle-guide secured directly to the end of said shaft without intervening parts, whereby the two may be manipulated as one piece, and a needle mounted to oscillate coaxially with said rock-shaft.
15. In a sewing-machine, a needle-guide mechanism comprising a rock-shaft or spin-

dle mounted to oscillate in the head of the machine, a needle-guide secured immediately to one end of said spindle in fixed relation thereto whereby the spindle and needle-guide may be together mounted and dismounted, and an arcuate needle projecting through a hole in said needle-guide and arranged to oscillate coaxially with said spindle.

16. In a sewing-machine, a needle-guide mechanism comprising a stationary sleeve or bushing secured in the work-head of the machine and having a projecting end, a rock-shaft mounted therein, means for oscillating said rock-shaft, a needle-block mounted on said projecting end, and a needle-guide secured immediately to the projecting end of said rock-shaft whereby the spindle and needle-guide may be together mounted and dismounted.

In witness whereof I have hereunto set my hand in the presence of two witnesses.

JOSEPH LOUIS KIEFFER.
